United States Patent Office

Des. 207,411
Patented Apr. 11, 1967

207,411

SPICE RACK

William C. Diesinger, Jr., 624 Morris Ave.,
Bryn Mawr, Pa. 19010

Filed Apr. 26, 1966, Ser. No. 2,036

Term of patent 14 years

(Cl. D44—29)

FIG. 1 is a perspective view of a spice rack showing my new design;

FIG. 2 is a plan view thereof;

FIG. 3 is a front elevational view thereof;

FIG. 4 is a bottom view thereof; and

FIG. 5 is a side elevational view.

I claim:

The ornamental design for a spice rack, substantially as shown.
